UNITED STATES PATENT OFFICE.

HAROLD E. McCRARY, OF APOLLO, PENNSYLVANIA, ASSIGNOR TO PITTSBURGH STEEL DRUM COMPANY, OF PITTSBURGH, PENNSYLVANIA, A CORPORATION OF DELAWARE.

SHIPPING DRUM AND METHOD OF ASSEMBLING THE SAME.

Application filed February 9, 1926. Serial No. 87,080.

This invention relates to metal drums and a method of assembling the same.

An important object of the invention is to provide a novel method of assembling the body portions of shipping drums formed of light gage metal to prevent the seam thereof from opening when the drum is filled with relatively heavy material.

A still further object is to provide a novel seam construction for a metal drum employing fastening elements associated with the seam to prevent the latter from opening.

A still further object is to provide a shipping drum adapted to be formed of light gage metal having an interlocking seam, the seam being provided with openings and a non-metallic strip being arranged against the seam inwardly thereof and adapted to receive fastening elements driven therein through the openings in the seam.

A still further object is to provide fastening elements provided with pointed ends, such as tacks or the like, the fastening elements being longer than the combined thicknesses of the seam and packing strip whereby the latter may be placed upon a suitable anvil to turn the ends of the fastening elements back into the strip when the fastening elements are driven into position.

Other objects and advantages of the invention will become apparent during the course of the following description.

In the drawings I have shown one embodiment of the invention. In this showing:

Figure 1 is a central vertical sectional view.

Figure 2 is a detail transverse sectional view through the seam showing the method of assembling the elements.

Figure 3 is a detail longitudinal sectional view through one side of the drum showing it in position on the anvil, and,

Figure 4 is a detail fragmentary sectional view taken longitudinally through the seam and associated elements.

Referring to the drawings the numeral 10 designates the body of the drum preferably formed of light gage material, preferably sheet steel having wooden or other heads 11 arranged therein. The ends of the body are provided with inwardly turned flanges 12 to which metallic heads may be secured in any suitable manner, if desired. The body

of the drum is provided with inwardly extending beads 13 against which the heads 11 rest and is further provided with series of reinforcing ribs 14 extending throughout the greater portion of the circumference of the drum.

Referring to Figure 2, the numeral 15 designates an interlocking seam formed at the edges of the body portion of the drum. In forming the seam, lips 16 are turned backwardly from the body of the drum and are adapted to engage each other whereby a plurality of overlapping thicknesses of metal are provided. The seam 15 is provided with a series of spaced openings 17 extending through the successive thicknesses of the metal and fastening elements 18 are adapted to be arranged in these openings in a manner to be described. A strip of non-metallic material 19 is arranged against the inner face of the seam, as shown in Figures 2 and 4. The strip 19 is preferably formed of wood so that the fastening elements may be readily driven thereinto, as will be apparent. The fastening elements employed are provided with heads 20 and pointed ends 21, and the fastening elements are of a length substantially greater than the combined thicknesses of the seam 15 and strip 19. In assembling the elements just described, the body of the drum is adapted to be placed over an anvil 22 with the strip 19 arranged in a longitudinal groove 23 formed in the anvil.

In practice I prefer to provide the body of the drum with reinforcing beads 24 arranged adjacent and parallel to the seam to assist in preventing outward buckling thereof although these beads are not essential. The reinforcing beads 14 preferably extend to points adjacent the beads 24, as shown in Figure 1.

In assembling the drum, the seam 15 is formed in the usual manner and the elements thereof are assembled and rolled to provide a tight joint as will be apparent. The spaced openings 17 are then punched or otherwise formed in the seam to receive the fastening elements 18. The strip 19 is then arranged in the groove 23 and the drum is placed in position with the seam 15 arranged against the upper face of the strip 19, as shown in Figure 2. The fastening elements

are then driven into the strip 19 through the openings 17 until the heads 20 of the fastening elements contact with the outer face of the seam 15. As previously stated, the length of the fastening elements is substantially greater than the combined thicknesses of the seam 15 and strip 19, and accordingly the point of the fastening elements will contact with the anvil 22 before the heads 20 contact with the outer face of the seam. It will be apparent that if the fastening elements are driven downwardly to cause the heads thereof to snugly contact with the outer face of the seam, the points 21 of the fastening elements will be turned upwardly into the strip 19, thus securely anchoring them in position. It has been found that light gage sheet steel is not adaptable for use in connection with shipping drums where the latter are used for shipping relatively heavy material owing to the flexibility of the metal which causes the seams to open. It has been found that the provision of rivets for securing the seams against opening is too expensive for commercial use owing not only to the cost of the rivets but also to the cost of assembling. Accordingly the present method and structure is provided for turning the points of the fastening elements into the wood or other strip 19 serving to firmly anchor the fastening elements in position and thus preventing loss of the fastening elements. Thus it will be obvious that a drum formed according to the present method is adapted to be used for shipping heavy materials without danger of the seams opening during use.

It is to be understood that the form of the

invention and the method herein described are to be taken as preferred examples of the same and that various changes in the practice of the method and in the size, shape and arrangement of parts may be made without departing from the spirit of the invention or the scope of the subjoined claims. 45

I claim:

1. The herein described method of assembling sheet metal drums which consists in forming an interlocking seam at the edges of the material forming the body of the drum, providing said seam with an opening, placing a strip of material on an anvil, arranging the inner face of the seam on said strip of material, and driving a fastening element into said strip of material through said opening whereby the end of said fastening element will contact with the anvil and be turned back into said strip of material. 55

2. A shipping drum comprising a sheet metal body provided with an interlocking seam having a plurality of spaced openings therethrough, a strip of material arranged against the inner face of said seam, and a fastening element driven into said strip of material through each of the openings in said seam, said fastening elements having heads at their outer ends adapted to be driven into contact with the outer face of said seam, said fastening elements being longer than the combined thicknesses of said seam and said strip of material and having pointed inner ends turned back into said strip of material. 70

In testimony whereof I affix my signature

HAROLD E. McCREERY.
